[57] CLAIM

The ornamental design for the shoe hanger, as shown and described.

DESCRIPTION

FIG. 1 is a front elevational view of the shoe hanger showing my new design, the broken line showing of the shoes being for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
